UNITED STATES PATENT OFFICE.

CHARLES B. HATFIELD AND ADOLPH SORGE, JR., OF ROCHESTER, NEW YORK; SAID HATFIELD ASSIGNOR TO THE ROCHESTER SHOE MACHINERY COMPANY, OF SAME PLACE.

BUTTON AND BUTTON-HOLE MARKING MACHINE.

SPECIFICATION forming part of Letters Patent No. 365,126, dated June 21, 1887.

Application filed April 20, 1887. Serial No. 235,559. (No model.)

To all whom it may concern:

Be it known that we, CHARLES B. HATFIELD and ADOLPH SORGE, Jr., citizens of the United States, residing at Rochester, in the county of Monroe and State of New York, have invented a new and useful Button and Button-Hole Marking Machine for Boots and Shoes, of which the following is a specification.

Our invention relates to improvements in button and button-hole marking machines in which the upper of a boot or shoe, after the fly and the two quarters have been stitched together, has marks put upon it to indicate the positions of the buttons and button-holes; and the following is a full and clear specification describing the same with the accompanying drawings, and the novel features thereof specified in the claims annexed to the said specification.

In the accompanying drawings, Figure 1 is a plan view of our machine with the upper platen down. Fig. 2 is a section through the lower platen on the line *xx* of Fig. 1. Fig. 3 is a plan view with the upper platen raised, and showing an upper in position, several of the parts being shown broken, so as to more clearly illustrate the arrangement. Fig. 4 is a section through the marking device. Fig. 5 is a side elevation, and Fig. 6 a plan view of same. Fig. 7 is a side elevation of the machine with the upper platen raised. Fig. 8 is a section through the marking device, showing its position with regard to the upper when in operation. Fig. 9 is a side elevation of the machine with the upper platen down, and showing the upper and the marking device in position.

A A represent the lower platen or base of our machine. It can be made in any desirable shape, but preferably as shown, so as to nearly conform to the shape of the boot or shoe uppers. It has a flat upper surface, and at or near its back are two lugs, *aa*, which are drilled to permit studs to revolve in them. To these studs are fastened the lugs *bb*, formed on the ends of the extended arms of the upper platen, B B, which can thus swing above the lower platen or base. The lower face of the platen B B also has a large flat surface corresponding to the surface of A A. The lever C is attached

to the rear end of the platen B B, and is provided at its end with an eye, through which a pin or bolt can be passed to hold a connecting-rod, which is worked by a treadle under the table on which the machine is set, (not shown in the drawings,) or in any other suitable manner may have a swinging movement imparted to it. The studs, which are fastened in *bb*, extend out so that the lugs *cc*, which are drilled to fit the studs, may be placed upon them. These lugs *cc* are formed on the ends of the arms which carry the upper clamp, E E, which can thus swing around the studs between the upper and lower platens. A latch, F, is attached to a projection of the upper clamp and has a spring behind it, so as to force it forward over the edge of the platen B B, and a thumb-piece above to enable the operator to pull it back. The upper clamp can be made of any desired shape. Either a scalloped plate, as shown, or a wire of sufficient stiffness may be used.

In the surface of the lower platen, A A, slots are provided, as shown at *ff*, through which the wedges of the lower clamp, D, project downward. This lower clamp is made of a shape corresponding to the shape of the upper clamp, and has lugs near its ends on the under side, to which are attached rods, which pass through the platen A A and have tension-springs *gg*, so drawing the clamp down onto the surface of platen A A. Under the platen A A is a slide, G G, having wedges *ee*, corresponding to the wedges *ff* of clamp D. This slide is held in position by screws and washers passing through slots in same and secured in the bottom of platen A A. A small lever, *h*, is hinged under the platen A A at *d*, and has a hole in it, which sets over a pin on the upper surface of slide G G. The end of the lever projects through a slot provided in the base A A, and has a thumb-piece or handle at its end, by which it can be thrown to either side.

H, Figs. 4, 5, 6, 8, and 9, represents the rod of the marking device, which has a handle attached to one end. To the other end of this rod is attached an upright, I, made of steel or other suitable material. The upper face of this upright is provided with a suitable mark, which we prefer to make of the shape shown—

namely, a small conical projection, *m*; but this mark can be made of any desired form. The lower face of the upright is countersunk to correspond with the mark *n* on the spring-die *K*, which is attached to the upright by means of the spring *J*, as shown in Figs. 4, 5, 6, and 8. Two small gage-pins, *ll*, are also attached to the lower die, as shown in Figs. 5 and 6, and are so placed that when they are drawn into the notches between the scallops of the fly the mark *n* shall be in the position under the fly where it is desired to mark the location of the button-hole.

In operating the machine to mark the uppers of boots or shoes, the two quarters *M* and *L* having first been stitched together and the fly *N* secured to the quarter *L* in the usual manner, the lever *h* is thrown over to the left, thereby moving slide *G G*, and the wedges *ee*, 15 pressing on the wedges *ff* of the clamp *D*, raise the latter from the surface of *A A*. At the same time the latch *F* is thrown back, thus releasing the upper clamp, *EE*, which will now rest upon the lower clamp, while a pressure of 20 the foot upon the treadle (not shown) raises the upper platen, *B B*. The upper of the boot or shoe is now introduced, the joint between the fly *N* and the quarter *L* being passed under the raised lower clamp, and the upper quarter, *M*, 25 being laid loosely on the lowered upper clamp. The whole upper thus lies freely without any force to throw it out of shape, and can adjust itself naturally. The lever *h* is now thrown to the right, the wedges *ee* allowing 30 the wedges *ff* and lower clamp, *D*, to be drawn hard down and firmly clamp the fly and lower quarter by means of the tension-springs *gg*. The pressure is removed from the treadle and the upper platen, *B B*, descends, its edge striking 35 the incline on the latch *F*, which is forced back until the platen *B B* is down and the latch snaps over the edge of the platen, thus securely holding the upper quarter, *M*, between the upper platen, *B B*, and upper 40 clamp, *EE*. The upper platen, carrying the quarter *M*, is now raised, and the marking device is introduced by passing the spring-die *K* between the fly *N* and lower quarter, *L*, as shown in Fig. 8, until the pins *ll* strike fairly 45 in the notches between the scallops. The upper platen is now made to descend, carrying with it the quarter *M*, until it strikes the up-

right *I* and the necessary force is exerted to make an impression or mark on the lower side of quarter *M* and of fly *N*. The upper platen 55 is again raised and the marking device shifted to the next scallop, when it is again brought down with sufficient force to make the marks. This is repeated until all the scallops are marked, and thereby corresponding places on 60 the quarter *M*, whereupon the lower and upper clamps are again loosened, as before described, and the boot or shoe upper is removed to make place for another, on which the same operations are repeated.

Having now described the construction and operation of our invention, what we claim is—

1. The combination, in a button and button-hole marking machine, of the lower platen, *A A*, with its clamp *D*, and the upper swinging platen, *B B*, with its clamp *EE*, substantially as described.

2. The combination, in a button and button-hole marking machine, of the lower platen, *A A*, with its clamp *D*, the upper swinging platen, *B B*, with its clamp *EE*, and the marking device *I*, with its spring-die *K J*, substantially as described.

3. The combination, in a button and button-hole marking machine, of the lower platen, *A A*, with its clamp *D*, the upper swinging platen, *B B*, with its clamp *EE*, the marking device *I*, with its spring-die *K J*, and the slide *G G*, with its wedges *ee*, and a suitable lever, *h*, substantially as described.

4. The combination, in a button and button-hole marking machine, of the lower platen, *A A*, with its clamp *D*, the upper swinging platen, *B B*, with its clamp *EE*, the marking device *I*, with its spring-die *K J*, the slide *G G*, 85 with its wedges *ee*, and a suitable lever, *h*, with a latch, *F*, for securing or releasing the upper clamp, substantially as described.

5. The combination, in a button and button-hole marking machine, of the upright *I*, attached to a rod, *H*, and having a spring-die, *K J*, secured to it, and provided with suitable raised marks and countersinks, *m* and *n*, and gage-pins *ll*, substantially as described.
